WRINGER WITH UPSWEEP RESET HANDLE

Nicholas L. Etten, Waterloo, Iowa

Application November 27, 1939, Serial No. 306,308

10 Claims. (Cl. 68—263)

This invention relates to clothes wringers and more particularly to an improved wringer reset device for establishing initial operating pressure between the rolls of the wringer after the emergency release mechanism of the wringer has been actuated.

The principal object of the invention is to provide a clothes wringer with a reset lever adapted to stand in vertical position during the operation of the wringer and pivoted at its lower end in order that the wringer pressure spring may be reset by arcuate movement of the lever in an upward direction.

Another important object of the invention is to provide a wringer structure wherein the reset lever is mounted on a pivot point solidly fixed with respect to a stationary wringer frame.

A further object of the invention is to provide a wringer having a main frame and a separable top frame with latching means and a pressure reset lever of such design and construction that the actuation of the pressure reset lever alone will move the cooperating latch members toward each other and interlock these latch members while the wringer top frame remains in a position somewhat spaced apart from the main frame of the wringer; and wherein the return movement of the pressure reset lever will be effective to draw the separable top frame downwardly into normal operating relationship with the main frame.

A further important object of the invention is to provide a wringer attractive in design, dependable in operation, and economical in manufacture.

The preferred embodiment of the present invention illustrated in the drawings includes the conventional main frame and separable top frame provided with suitable release bars effective to release the latch mechanisms securing these frames in operating position in order to release the operating pressure between the rolls. This device is distinguished from the prior art structures, however, by virtue of the fact that the operation of the wringer reset devices has been greatly simplified and the wringer may be reset by the single act of swinging the reset lever downwardly about a fixed pivot point and then returning this lever upwardly to its original position. This mode of operation is in sharp contrast with the operation of the prior art structures known to the applicant, in most of which it is necessary to manually manipulate the entire top head of the wringer to engage latch mechanisms at one end, to manually manipulate cer-

tain latch mechanisms themselves at the opposite end of the wringer to bring these latches into engaged locking position, and to thereafter re-establish pressure by the operation of some form of reset lever.

The particular structure by which the applicant accomplishes these desirable results will be readily understood by reference to the accompanying drawings forming a part of this specification in which:

Fig. 1 is a front elevation of a wringer constructed in accordance with the principles of this invention, certain parts of the wringer housing being shown broken away to more clearly illustrate the wringer mechanism;

Fig. 2 is a fragmental plan section through the wringer top frame, taken substantially on the plane of the line 2—2 of Fig. 1;

Fig. 3 is a detail sectional view through one of 20 the vertical bearing slideways of the wringer and is taken substantially on the plane of the line 3—3 of Fig. 1;

Fig. 4 is a detail sectional view through the wringer latch mechanism and is taken substantially on the plane of the line 4—4 of Fig. 1;

Fig. 5 is a detail sectional view through the wringer reset lever and associated latch mechanisms illustrating the wringer rolls in released position;

Fig. 6 is a detail sectional view similar to Fig. 5 illustrating the resetting operation of the wringer;

Fig. 7 is a fragmental perspective view of the wringer latch and cooperating mechanisms; and

Fig. 8 is a perspective view of the latch slide.

The wringer chosen for purposes of illustration of the present invention comprises in general a lower roll 10 and an upper roll 11 mounted in vertical bearing slideways carried by the lower 40 frame 12 of the wringer structure. The wringer is preferably provided with a mounting sleeve 13 which may be telescoped into a cooperating mounting column such as is customarily provided on modern washing machines. The rolls 10 and 11 are adapted to be power driven in either forward or reverse direction, controlled by the operation of a gear shift 14 adapted to control a conventional reversing gear assembly housed within the end portion 15 of the lower wringer frame.

A separable top frame or cross head 16 is latched to the main frame 12 and is provided with a pressure adjusting screw 17 adapted to bear at the approximate center point of a flat pressure spring 18 extending between the movable upper roll bearings 19 in which the upper roll 11 is jour-

naled. The structures thus far described are commonly known in the prior art, and since they do not constitute the essence of the present invention, they will, therefore, not be described in greater detail in this application.

The structure of the release and reset mechanism forming the subject matter of this invention includes a reset lever 21 pivotally mounted on a pivot pin 22 rigidly secured in a pivot pin bracket 23 secured adjacent the lower end of the vertical bearing slideway 24 of the main wringer frame 12. An operating link 25 is pivotally mounted on a pivot pin 26 extending between opposed side flanges 30 formed on the reset lever 21 and extends downwardly from the pivot pin 26 to a similar pivot pin 27 mounted on the vertical latch slide 28. By reference to the drawings it will be seen that each of the operating parts of the reset mechanism is formed in a somewhat channel-shaped cross section, each including a pair of opposed side flanges through which the pivot pins penetrate, joined by an intermediate body portion formed integrally with the side flanges. This construction is preferred since it is capable of economical manufacture and provides a rugged structure capable of standing great abuse, but it is not essential to the practice of the principles of this invention. The bearing slide 28 is positioned inside of a channel-shaped vertical bearing slideway 24, but the side flanges 29 extend outwardly through a pair of slots 35 formed in the end wall 35 of the bearing slideway and are provided with a pair of perforations 37 to accommodate the pivot pin 27 on which the operating link 25 is pivoted. The flanges 29 of the vertical latch slide 28 are also provided with a pair of perforations 38 in which a latch pivot pin 39 is mounted. The latch 41 also comprises a flat body portion 42 extending between two opposed side flanges 43, each of which is perforated at 44 in order to form a pivotal mounting for the latch on the latch pivot pin 39. A triangular latch engaging block 45 is welded to the extreme upper end of the latch 41 to provide two angular surfaces 46 and 47 to guide the latch into engaging position and to engage the cooperating latch mechanism as will be more fully set forth hereinafter, and a positioning stop 40 is provided at the lower end of the latch 41 to limit the pivotal movement of the latch 41 about the pin 39.

A vertically extending locking lug 48 is also provided at the extreme top of the latch 41, and this locking lug 48 is positioned between a pair of limiting stops 49 formed at right angles to the lug 48. These latch mechanisms are adapted to operatively engage a top latch 51 welded inside of the top frame or cross head 16. The top latch 51 includes an angularly inclined surface 52 which will be engaged by the angular surface 46 of the triangular latching block 45 to guide the latch 41 into engaging position and an angular surface 53 which will co-act with the angular surface 47 of the triangular latch bar to retain the top frame 16 in operating position. The angular inclination of the surfaces 53 and 47 is such that the force exerted by the pressure spring 18 would cause them to disengage unless additional latch locking mechanisms are provided. From this it will be understood that the latching surfaces 47 and 53 form an unstable latch which will release unless the separation of these latching surfaces is prevented by a second or auxiliary latch comprising in the present structure an angularly shaped latching member 55 extending

between a pair of latch releasing arms 56 pivoted inside of the top frame 16 on a pair of rivets 57 mounted in the opposed side walls of the top frame.

5 In normal position the latch member 55 rests lightly upon the two limit stops 49 and is thus held in position to be engaged by the lug 48 to prevent the latch 45 from becoming disengaged from the latch 51. The emergency release bars 10 61, positioned on each side of the top frame 16 of the wringer, are pivotally mounted on rivets 62 and are provided with trigger portions 63 extending into the wringer top frame 16 through the two suitable punched openings 64 to a position immediately below and co-acting with lugs 65 formed on each of the opposed arms 56. The arrangement is such that whenever either of the emergency release bars 61 is manually actuated, the release bar will pivot around the rivets 20 62 to move the trigger portion 63 upwardly into engagement with the lug 65 and lift the arms 56 sufficiently to cause the angular latch member 55 to disengage the lug 48 on the latch 41. This will cause the latch 41 to be released from the latch 51 since the angular relationships of the surfaces 47 and 53 is such that the latch is unstable and the pressure exerted by the pressure spring 18 will act upwardly on the top frame to exert a camming action between these surfaces 30 sufficient to pivot the latch 41 about the pin 39 and against the relatively light tension exerted by the spring 66. When thus released the top frame 16 will move upwardly sufficiently to release the spring pressure exerted between the rolls 35 and sufficiently to allow the rolls to separate to any degree necessary to relieve the pressure on any body positioned within the bite of these rolls. When there is no object between the rolls, however, the weight of the top frame 16 will cause 40 this frame to swing downwardly about the pivot pin 68 until its movement is limited by engagement with the flat pressure spring 18. At this time since there is no pressure exerted to cause flexing of the pressure spring, the top frame 16 will be held in spaced apart relationship with the main frame 12, but the pivot pin 68 will control the movement of the top frame sufficiently that the latching member 51 will be in a position substantially directly above the position it assumes 45 during the operation of the wringer.

At this point it should be noted that the pivot pin 68 is mounted on the extreme end of the portion 15 of the lower frame 12, and is thus quite remote from the position of the pressure adjusting screw 17 or either of the wringer roll bearings 19. This arrangement is advantageous in that it permits a complete pressure release on both ends of the upper roll 11, which is not satisfactorily accomplished in prior art by structures in which the top head was pivoted at a point so close to one of the bearings that the mere weight of the top frame exerted considerable pressure and prevented complete release of one end of the upper roll.

65 To reset the wringer it is unnecessary for the operator to touch the top frame of the wringer in any way, nor is it necessary to manually manipulate any latching mechanisms. The resetting of the device is accomplished by simply swinging the reset lever 21 downwardly about the pivot point 22 and then upwardly into its original position.

70 On the downward stroke the lever 21 acts to move the lower latch mechanism directly upwardly on the slide heretofore described, until 75

the cooperating latch members engage and interlock, and on the upward stroke of the lever the top member 16 is drawn downwardly toward the frame 12 to compress the flat pressure spring 18 and apply the initial pressure between the wringer rolls. In this connection it should be pointed out that certain important advantages are gained by pivoting the reset lever on a stationary pivot at the lower end of the lever. These advantages arise from the fact that modern power-operated wringers are operated at relatively high speeds and must be provided with a correspondingly high initial operating pressure to insure satisfactory wringing. The prior art structures known to the applicant have been objectionable in that they have been difficult of operation, particularly in cases where the operator is a woman of small stature or of limited physical strength. For one thing, the downward swing of the customary type of reset lever is awkward for a person of small stature to operate. This is overcome in the present device since the upsweep of the lever illustrated permits even a child to exert considerable force, since the operator may in fact brace herself against the floor and push upwardly; whereas, with downwardly swinging devices, the operator has no means of bracing herself. A further advantage is gained in the present structure by providing an absolutely solid pivot point for the lever as contrasted with a shaky or unsteady pivotal mounting, as for example, a pivot affixed to a releasable head or top frame.

The detailed operation of the wringer mechanism is as follows: When the operator swings the reset lever downwardly about the pivot 22, the operating link 25 will act between the pivots 26 and 27 to move the latch slide 28 upwardly along the inner wall of the bearing slideway 24. The latch 41, which is carried by pin 39 affixed to the bearing slide 28, and maintained in fixed position by the spring 66 and the stop 40, will move upwardly toward the latch 51, and as the angular surface 46 engages the angular surface 52, the latch 41 will pivot slightly about the pin 39 and continue its upward movement until the angular surface 47 has come into full engagement with the angular surface 53. As this position is reached the latch 41 will return to its original position under tension exerted by the coil spring 66, and the lug 48 will lock the latch assembly in engagement. It will be appreciated that as the reset lever 21 is swung downwardly and the latch 41 moves up, the lug 48 will contact the lower surface of the latch member 55 and lift it upwardly. However, when the lug 48 moves to the left the angular latch member 55 will drop downwardly under the influence of gravity and come to rest on the stop portions 49 formed on the top of the latch 41 to lock the latch 41 in full locking engagement with the top latch 51.

The operator will now swing the reset lever upwardly to normal operating position, and as this is done the operating link 25 will act between the pivot points 26 and 27 to draw the latch slide 28 and the latch 41 bodily downward a sufficient amount to return the top frame to its original operating position. This movement will, of course, compress the spring 18 and apply operating pressure between the rolls, but since the pivot point 26 moves beyond the dead center line established through the pivot points 22 and 27, the pressure will not cause the reset lever 21 to spring outwardly, but instead will retain this lever in vertical position at the end of the wringer frame.

From the foregoing description it will be apparent that the present invention provides a wringer structure in which a releasable top head of a wringer may be automatically engaged, latched, and drawn downwardly into cooperating engagement with the lower frame by the single act of moving the reset lever and without the necessity that the operator manipulate either the top frame itself or any latch mechanisms adapted to interlock the top frame with the main frame.

While I have shown and described a preferred embodiment of this invention in compliance with the patent statutes, I am aware that it is subject to numerous alterations and modifications without departing from the spirit of the invention, and I, therefore, do not wish to be limited except as by the scope of the appended claims.

I claim:

1. In a wringer comprising a pair of pressure rolls, a pressure spring, and a pair of relatively movable frame structures comprising a stationary frame and a relatively movable frame normally urged apart into spaced relationship by the pressure spring and adapted to be secured together in operating position to compress the pressure spring and apply operating pressure between the pressure rolls, the combination of cooperating latch mechanisms associated with each of said frames adjacent one end of said frames, positioning means comprising a pivotal connection between said frames at the end remote from said latch mechanisms to position said frames and latch mechanisms in predetermined spaced-apart relationship, a reset lever pivotally mounted on a fixed pivot on said stationary frame, means comprising a link and shiftable latch support interconnecting said reset lever and one of said latch mechanisms to shift said latch mechanism with respect to its associated frame, means responsive to said shifting movement to guide said latch mechanism into interlocking engagement with the cooperating latch mechanism, and spring means to cause said latch mechanisms to interlock.
2. In a wringer comprising a pair of pressure rolls, a pressure spring, and a pair of relatively movable frame structures comprising a stationary frame and a relatively movable frame normally urged apart into spaced relationship by the pressure spring and adapted to be secured together in operating position to compress the pressure spring and apply operating pressure between the pressure rolls, the combination of cooperating latch mechanisms associated with each of said frames, positioning means to position said frames and latch mechanisms in predetermined spaced-apart relationship, a reset lever pivotally mounted on said stationary frame, means comprising a link and shiftable latch support interconnecting said reset lever and one of said latch mechanisms to shift said latch mechanism with respect to its associated frame, means responsive to said shifting movement to guide said latch mechanism into interlocking engagement with the cooperating latch mechanism, and spring means to cause said latch mechanisms to interlock.
3. In a wringer comprising a stationary lower main frame, a top frame relatively movable with respect to said main frame, a pressure spring and a plurality of pressure rolls, the combination of a stationary reset lever pivot fixedly associated with said main frame at right angles to the axis of said pressure rolls, a manually operable reset

lever mounted on said pivot and adapted to extend vertically upwardly from said pivot adjacent the end of said main frame, a movable latch support associated with said main frame, an operating member interconnecting said latch support and said reset lever whereby said latch support may be shifted responsive to the operation of said reset lever, latch means carried by said latch support, a latch member carried by said top frame, and positioning means for said top frame to positions and latch means and latch member in predetermined spaced-apart relationship.

4. In a wringer comprising a stationary lower main frame, a top frame relatively movable with respect to said main frame, a pressure spring and a plurality of pressure rolls, the combination of a stationary reset lever pivot fixedly associated with said main frame, a manually operable reset lever mounted on said pivot and adapted to extend vertically upwardly from said pivot adjacent the end of said main frame, a movable latch support associated with said main frame, means whereby said latch support may be shifted relative to said frame, latch means carried by said latch support, cooperating latch means carried by said top frame, and means responsive to the shifting movement of said first named latch means to guide said latch means into interlocking position while said frame members remain in spaced-apart relationship.

5. In a wringer comprising a stationary lower main frame comprising spaced-apart vertical bearing slides and a longitudinal member interconnecting said slides, a top frame extending between said bearing slides and relatively movable with respect to said main frame, a pressure spring and a plurality of pressure rolls, the combination of a stationary reset lever pivot fixedly associated with said main frame at right angles to the axis of said pressure rolls, a manually operable reset lever mounted on said pivot and adapted to freely swing arcuately outwardly and downwardly from the end of the wringer frame and to be reset against the resistance of the pressure spring by manual movement upwardly and in a direction directly toward the point of support of the wringer frame; top and bottom latch mechanisms associated with said top and main frames respectively, and means responsive to the operation of said reset lever to move said latch mechanisms toward each other, to guide said latch mechanisms into interlocking engagement while said frames remain in spaced-apart relationship, and to move said frames into operating position against the resistance of the pressure spring.

6. In a wringer comprising a stationary lower main frame, comprising spaced-apart vertical bearing slides and a longitudinal member interconnecting said slides, a top frame extending between said bearing slides and relatively movable with respect to said main frame, a pressure spring and a plurality of pressure rolls, the combination of a stationary reset lever pivot fixedly associated with said main frame, a manually operable reset lever mounted on said pivot and adapted to freely swing arcuately outwardly and downwardly from the end of the wringer frame and to be reset against the resistance of the pressure spring by manual movement in an arcuate upward path; top and bottom latch mechanisms associated with said top and main frames respec-

tively, and means responsive to the operation of said reset lever to move said latching mechanisms toward each other, to guide said latch mechanisms into interlocking engagement while said frames remain in spaced-apart relationship, and to move said frames into operating position.

7. In a wringer, comprising a lower frame, a top frame relatively movable with respect to said main frame, pressure rolls, and a pressure spring; the combination of a manually-operable toggle reset lever pivoted on said lower frame and adapted to extend vertically upward adjacent the end of said frame, a toggle link pivoted to said reset lever, cooperating latch mechanisms associated with each of said frames adjacent one end, and a shiftable member connecting said cooperating latch means with the manual reset lever and link whereby the top frame may be moved to a fixed position upon the lower frame with pressure upon the rolls by an upward arcuate movement of the manual reset lever.

8. In a wringer, comprising a lower frame, a top frame relatively movable with respect to said main frame, pressure rolls, and a pressure spring; the combination of a manually-operable toggle reset lever pivoted on said lower frame and adapted to extend vertically upward adjacent the end of said frame, a toggle link pivoted to said reset lever, cooperating latch mechanisms associated with each of said frames adjacent one end, a shiftable member connecting said cooperating latch means with the manual reset lever and link whereby the top frame may be moved to a fixed position upon the lower frame with pressure upon the rolls by an upward arcuate movement of the manual reset lever, and a manually-operated safety mechanism for quickly releasing the cooperating latches to permit upward movement of the top frame and release of pressure.

40 9. In a wringer, comprising a lower frame, a top frame pivotally supported over the lower frame at one end for movement to a position on the lower frame in normal operating position and detached therefrom when released under pressure, pressure rolls in the lower frame, and a pressure spring; the combination of manually-operable toggle reset mechanism pivoted on said lower frame, cooperating latch mechanisms associated with each of said frames, and a shiftable member connecting said cooperating latch means with the said manually-operable toggle reset mechanism whereby the top frame may be moved to a fixed position upon the lower frame with pressure upon the rolls by an upward arcuate movement of the lever.

10. In a wringer, comprising a lower frame, a top frame pivotally supported over the lower frame at one end for movement to a position on the lower frame in normal operating position and detached therefrom when released under pressure, pressure rolls in the lower frame, and a pressure spring; the combination of cooperating latch mechanisms associated with each of said frames adjacent their opposite ends, a shiftable member, and manually-operable toggle reset mechanism pivoted on the lower frame and co-acting with said latch mechanisms by interaction of the shiftable member to move the top frame to a fixed position upon the lower frame with pressure upon the rolls.

NICHOLAS L. ETTEN.
